DEWATERING, SEPARATING AND CLASSIFYING APPARATUS

Marvin E. Ginaven, Springfield, Ohio, assignor to The
Bauer Bros. Co., Springfield, Ohio

Filed Sept. 23, 1971, Ser. No. 183,305

Term of patent 14 years

Int. Cl. D23—01

U.S. Cl. D23—4

FIG-1

FIG-2

FIG-3

FIG-4

FIG-5

FIG-6

FIG. 1 is a perspective view of a dewatering, separating and classifying apparatus embodying my new design;

FIG. 2 is a top plan view thereof;

FIG. 3 is a perspective view of a modified form of the dewatering, separating and classifying apparatus as shown in FIG. 1;

FIG. 4 is a side elevational view of a second modified form of the dewatering, separating and classifying apparatus as shown in FIG. 1;

FIG. 5 is an end elevational view of FIG. 4; and

FIG. 6 is a top plan view of FIG. 4.

I claim:

The ornamental design for dewatering, separating and classifying apparatus, substantially as shown and described.
